LELAND S. HAMER, OF FULLERTON, CALIFORNIA

WELL DRILLING APPARATUS

Application filed July 9, 1923. Serial No. 650,289.

In drilling with the rotary method various parts are frequently screwed together and taken apart, this being particularly true of the stands of drill pipe employed to operate the bits. The parts thus connected and disconnected are usually handled by tongs, and it is often necessary, for instance, when disconnecting stands of drill pipe, to apply great force to the tongs in order to break the joints. With ordinary drilling apparatus the tongs are operated by a line having one end connected with the handle of the tongs and the other end arranged around a winch-head, termed the cat-head, of the draw works. A man has to arrange the line around the cat-head and pull it tight to cause it to grip the head. The man operating this line is constantly in danger, as occasionally the line fouls on the head and breaks or the tong is released from the work and is drawn toward the cat-head or draw works. This method of operating tongs, in addition to being more or less dangerous, requires considerable time as the line has to be arranged on the cat-head by hand every time the tong is operated.

It is a general object of this invention to provide an effective, improved apparatus for operating tongs, or the like.

A particular object of my invention is to provide a tongs operating apparatus which is always connected with the tongs ready to operate, and, therefore, does not have to be connected up or manipulated by hand before each operation.

Another object of my invention is to provide a tongs operating apparatus which is controlled by the driller from his usual position at the draw works removed from the point toward which the tongs is pulled, thus eliminating danger to the operator.

It is another object of this invention to provide a tongs operating apparatus which will operate the tongs a predetermined amount, and, therefore, will not draw the tongs into the draw works.

Another object of this invention is to provide a tongs operating mechanism such as I have above referred to which is adjustable as to leverage and the amount it operates the tongs.

A further object of my invention is to provide an apparatus, such as I have above referred to, which is applicable to an ordinary draw works as an attachment and without requiring changes in the construction or operation of the draw works. 55

The various objects and features of my invention will be best and more fully understood from the following detailed description of a typical preferred form and application 60 of my invention, throughout which descriptive reference is had to the accompanying drawings, in which:

Fig. 1 is a front elevation or face view of a typical draw works, provided with my 65 present invention;

Fig. 2 is an end view of the draw works shown in Fig. 1, being a view taken as indicated by the line 2-2 on Fig. 1;

Fig. 3 is a plan view of the parts shown in Fig. 2, being a view taken as indicated by the line 3-3 on Fig. 2; 70

Fig. 4 is an enlarged detail sectional view of a part of the apparatus provided by my invention, being a view taken as indicated by 75 the line 4-4 on Fig. 1;

Fig. 5 is an enlarged detail view showing the mechanism provided by my invention in its actuated position, being a view taken as indicated by the line 5-5 on Fig. 1; 80

Fig. 6 is a plan section, taken as indicated by the line 6-6 on Fig. 1;

Fig. 7 is a view similar to Fig. 5, showing the mechanism in its unactuated position; 85

Fig. 8 is an enlarged sectional view of a portion of the apparatus showing a modified form of construction.

My present invention is of such nature that it can be applied to or embodied in a well drilling rig independent of any of the other parts or mechanisms of the rig, it being desirable however that it be related to the rotary so that it can be effectively connected with tongs, or the like, applied to work arranged in or at the rotary, and that it have a suitable connection with a source of power, for instance, the engine that operates the other mechanisms of the rig. 90

In practice it is most convenient and ad- 100

vantageous to locate the operating parts provided by my invention at the draw works as the draw works is a unitary and standard part of a typical drilling rig, and is usually well suited for my invention. The invention is suitable for embodiment in or attachment to the draw works, either at the time the draw works is constructed or at any time thereafter. Practically all draw works in common use are such that the mechanism of the present invention can be applied to them without altering or disturbing them in any way. As it is advantageous that my invention be applicable to a draw works as an attachment that may be applied without changing or interfering with the draw works in any way, I will herein describe a form of my invention that can be readily applied to a draw works as an attachment, it being understood, however, that various features of construction of my invention might be varied or modified in case the invention is embodied in a draw works as a standard part.

To facilitate a clear and full understanding of my invention I have disclosed the invention as applied to or in combination with a typical draw works constructed and located in a rig in the usual manner.

The frame of the draw works is constructed as a permanent part of the rig and includes a horizontal head board or girth 10, located at one side of the derrick at a point above the derrick floor 11, a left hand upright 12, extending between the girth 10, and a sill 13 at the derrick floor 11, a right hand upright 14 extending between the girth 10 and sill 13, and a center upright 15 located between the uprights 12 and 14 and extending between the girth 10 and sill 13. A horizontal drive shaft 16 is mounted in the upper part of the frame, being carried in bearings 17 mounted on the rear sides of the uprights 12, 14 and 15. The drive shaft 16 is a comparatively heavy shaft, usually driven by an engine (not shown) located outside of the rig through a chain drive 18, or the like. A horizontal drum shaft 19 is carried by the frame below the drive shaft 16, it being mounted in bearings 20 mounted on the inner or front sides of the uprights 12 and 15. The drum shaft 19 has a comparatively large reel or drum 21 mounted on it between the uprights 12 and 15. In the particular draw works illustrated in the drawings the drum is of such size and is so located on the drum shaft 19 as to leave considerable clearance or space between the end of the drum and the center upright 15. The drum shaft 19 is adapted to be driven from the drive shaft 16 through a chain drive connection 22 and clutch 23 or a chain drive connection 24 and clutch 25. The speed ratios of the two driving connections 22 and 24 are different, making it possible to drive the shaft 19 at different speeds from the drive shaft 16. The

clutch 23, which controls the drive connection 22, is operable from a lever 30, at the left hand upright of the draw works, through a suitable control part or lever 26 and a yoke 27, while the clutch 25, which controls the drive connection 24, is operable from a lever 28, at the left hand upright, through a yoke 29. The rotary unit 31 located at the center of the derrick floor 11 is driven from the drive shaft 16 through a chain drive connection 32 and control clutch 33. The control clutch 33 of the rotary drive is located on the shaft 16 between the right hand upright 14 and center upright 15 and is controlled by a lever 34, located at the left hand upright 12, through connecting parts 35 and a yoke 36. The control levers for the various parts of the apparatus being located at the left hand upright of the draw works, the driller, who controls the various mechanisms of the rig, usually stands at the left end of the draw works when the rig is in operation.

The parts thus far described are those common to rotary well drilling rigs and the arrangement of parts may be considered typical of that usually employed.

The form of the present invention that I have set forth in the drawings is adapted to be applied or attached to the drive shaft 16 of the draw works. The mechanism includes, generally, a cam 37 adapted to be driven from the drive shaft 16 through a clutch 38; a lever or arm 39 adapted to be operated by the cam 37, and an operating connection 40 between the arm 39 and the member or tool to be operated. In the case of a draw work such as I have hereinabove described, the mechanism of the present invention is preferably mounted on or applied to the drive shaft 16 and other parts so that it is at or opposite the space between the end of the drum 21 and center upright 15. If the draw works is constructed so that there is no space between the drum and center upright, I may proportion and locate the mechanism of my invention at any point in the draw works where it will operate properly and avoid interference with the various parts of the draw works.

The cam 37 is preferably mounted directly on the shaft 16 so that it is freely rotatable on the shaft. In the form of the invention illustrated in the drawings the cam is comparatively large and has a circular rim 41, with a flat cam face 42, a hub 43, and spokes 44 which connect the hub and rim. The rim is, of course, supported eccentrically with relation to the hub so that the cam has the desired throw. The hub carries a suitable bearing 45 which freely fits the shaft 16. When the mechanism of my invention is to be attached to a draw works, or the like, as I am herein describing it, the cam 37 is formed in two separable sections adapted to be secured together around the shaft 16 by suitable bolts 46 and 47. The bolts 46 connect spokes which

abut when the sections of the cam are arranged together, while the bolts 47 connect the hub parts.

The clutch 38, in accordance with the preferred form of my invention, is a friction clutch. The clutch that I have illustrated in Figs. 1 to 7, inclusive, is of the cone type, and includes a female part 48 connected with the cam, and a male part 49 connected with the shaft 16, and adapted to be moved into and out of cooperative engagement with the female part. The female part 48 has a tapered opening 50 in it, lined with a suitable friction lining 51, and is provided at its inner 15 or small end with a flange 52 by which it is connected to the cam 37 by bolts 53. The female part 48 is formed in two sections so that it can be arranged or assembled around the shaft 16. The two sections of the female 20 part 48 may be secured together by bolts connecting flanges 54 provided at the abutting edges of the sections. In practice the female clutch part 48 is secured to the cam 37 so that its line of joinder is at right angles to that 25 of the cam, thus causing the cam and clutch sections to tie each other together. The male clutch part 49 is slidably keyed to the shaft 16 by a suitable key 55, and is provided with a tapered body part having a friction facing 56 30 and adapted to fit into the tapered opening in the female part 48. The male clutch part 48 is formed in two sections so that it can be arranged together or assembled around the shaft 16, and its sections being secured together by 35 suitable bolts 58. A stop collar 59 is applied to the shaft 16 so that it operates to limit the outward movement of the male clutch part.

Although the clutch 38 may be controlled in various manners, and may be controlled 40 from various points in the rig, I prefer to control it from a lever 61, or like part, located at the left hand upright of the draw works. The male clutch part may be controlled from the lever 61 through a shaft 62, 45 a rod 63, a lever 64, and a yoke 65. The yoke 65 is carried by the lever 64 and fits over the hub 60 of the male clutch part. The yoke carries blocks 66 which are slidably carried in an annular groove 67 provided in the hub 50 60. It will be obvious from inspection of the drawings, and particularly Fig. 1, how movement of the lever 61 will cause swinging of the yoke 65 and move the male clutch part 49 into and out of cooperative engagement 55 with the female clutch part 48. By thus providing the control lever for the clutch at the left hand end of the draw works the driller can conveniently operate it without leaving his post. I preferably provide means in 60 connection with the male clutch part or its operating mechanism for normally holding it in released position. In the drawings I have shown a spring 64a in connection with the girth 10 and lever 64 so that it operates to 65 yieldingly hold the male clutch part out.

The arm 39 is preferably arranged or mounted so that it is operated upon directly by the cam 37. It is convenient to pivotally connect the arm 39 to the girth 10 by a suitable bracket 70 and pivot pin 71 so that it 70 extends or hangs downwardly in engagement with the cam at the rear of the cam and draw works. Where the cam 37 operates on or cooperates with the arm 39 I provide a bearing shoe 72 having a flat bearing surface 73 to cooperate with the flat cam surface 42 of the rim of the cam, and having flanges 74 which extend on either side of the cam 41. The flanges operate to hold the arm and rim in proper alinement. In the arrangement that I have illustrated in the drawings the arm 39 is held against, or in cooperative engagement with, the cam by gravity, however, I prefer to aid the gravitational action by holding the arm in engagement with the cam by a spring 75 connecting the arm with a suitable bracket 76 mounted on the center upright 15. Further, when the axis of pivotal mounting of the arm 37 is located with relation to the point contact between the arm and cam, as 80 I have illustrated it in the drawings, I preferably bend or shape the arm so that its outer portion 77 is at an angle to its inner portion so that it is substantially vertical when midway between the two positions to which it is moved by the cam. However, it will be obvious that in practice the arm may, in any given case, be proportioned and shaped in the most advantageous manner. 85

The connection 40, provided by the present invention for connecting the arm 39 with a tool, for instance, a tongs 80, arranged on a drill pipe coupling 81 at a stand of drill pipe 82 carried in the rotary 31, includes, a yoke 84 and a flexible member or line 85. 100 When I herein use the term tongs I mean to include not only tongs but also any other tool or object that can be handled or operated upon by the mechanism I have provided. The yoke 84 faces toward the rear of the draw 105 works and has the outer ends of its arms connected with the arm 39 by a pivot pin 86. The arms of the yoke are spaced apart and shaped so that they will receive the cam and will operate without interfering with any 110 other parts of the mechanism. In order that the arms of the yoke may be connected with the arm 39 at a point substantially in line horizontally with the shaft 16, I preferably curve the outer portions 87 of the arms vertically, as I have illustrated in Fig. 5 of the drawings. In order that the yoke may be connected to the arm at various points I provide a series of holes or openings 89 along the arm 39 so that any one of them may be employed to carry the pivot pin 86. In the form of mechanism illustrated in the drawings, the yoke 84 is preferably reversed so that the parts 87 of the arm extend downwardly when the pivot bolt 86 is arranged in 115 120 125 130

an opening above or further inward than the one shown in the drawings. The inner end of the line 85 may be permanently connected with the yoke 84, while the outer end of the line 85 is adapted to detachably connect with the handle of the tool 80.

In accordance with my invention I may provide means for supporting the yoke 84 in a substantially horizontal position when the mechanism is not in operation. This means may include a bracket 90 mounted on the center upright and a projection 91 carried by the bracket so that it extends under the yoke. The projection may be in the form of a long bolt and the bracket may be provided at various points along its length with openings 92 so that the bolt may be arranged at different points to properly support the yoke when it is connected with different points on the arm 39.

In order that the cam and arm may operate to pull objects in directions other than directly toward them I provide vertical guide rollers 93 at the sides of the line 85 immediately in front of the draw works. The rollers 93 may be carried by shafts 94 supported by brackets 95 at the derrick floor, and brackets 96 connected with the girth 10. It will be obvious from inspection of Fig. 3 of the drawings how the rollers 93 operate to guide the line 85 so that the outer end of the line may be connected to an object at any point in the rig and will direct the inner end portion of the line so that the pull comes in the proper direction on the arm and cam.

I balance the cam and female clutch part by properly designing them and by applying suitable balance weights 100 and 101 to them so that the cam normally remains in the position illustrated in Fig. 7 where it projects toward the front of the draw works and allows the arm 39 to be in its in or forward position. When the cam has been rotated to another position, for instance, to the position illustrated in Fig. 5, by engaging the clutch, the weights and balancing of the cam and female clutch part will return it to its normal position as illustrated in Fig. 7 immediately upon the clutch being released.

In operation the clutch 37 is normally released and the cam 39 normally projects forward, as illustrated in Fig. 7, so that the arm 39 is forward. When the mechanism is operating tongs the tongs 80, having the line 85 connected to its handle, is arranged in place on the joint 81 so that the line 85 is fairly tight, or at least so that the most of the slack is out of it. To operate the tongs the driller, located at the left hand end of the draw works, operates the lever 61 so that the male clutch part moves into cooperative engagement with the female clutch part, causing the cam to rotate. The cam rotating moves the arm 39 rearwardly and the arm carries with it the yoke 84 which in turn pulls

the line 85, thus operating the tongs. If it is desired to operate the tong through a considerable distance the cam may be rotated through a full one hundred and eighty degrees to the position shown in Fig. 5, thus causing a maximum movement of the arm 39, and if the mechanism is connected, as I have illustrated in the drawings, and a greater movement is desired than can be obtained by a complete operation of the cam, the yoke 70 may be connected further out on the arm so that it has a greater movement. It will be apparent that any desired leverage or amount of movement may be obtained by suitably shaping the cam and by connecting the yoke 75 to the proper point on the arm 39. If it is desired to jerk the tongs, that is, to apply force to it suddenly, the lever 61 can be operated to throw the clutch in quick so that the cam is immediately locked with and driven 80 by the drive shaft, while, on the other hand, if it is desired to apply the force to the tongs smoothly and gradually this may be done by operating the lever so that the clutch eases in slowly and without grabbing. It will be 85 apparent that the driller has full control of the mechanism and that he can operate the tongs in any manner he may desire. Further, the line 85 may be left connected with the tongs so that the mechanism is ready for 90 operation as soon as the tongs is applied to the joint.

In Fig. 8 of the drawings I show another form of clutch that may be employed in carrying out my invention. This clutch, like the one hereinabove described, is a friction clutch, it being different from the one I have described in that its cooperating or gripping parts are in the form of flat plates. A flat clutch plate 110 is secured to the cam 37a, 100 while a corresponding flat plate 111 is carried at the end of a hub 112 slidably keyed to the shaft 16 by a suitable key 55. One of the plates is provided with a suitable friction facing 114. The hub 112 is adapted to be 105 moved on the shaft to move the plate 111 into and out of cooperative engagement with the plate 110. The hub may be moved through a yoke 65 connected with blocks 66 which operate in an annular groove 67 formed in the 110 hub.

From the foregoing description it will be apparent that my invention in its broader aspects is applicable to various situations, that is, to rigs and draw works of various 115 types or constructions, that the invention may be advantageously employed to operate tongs and various other parts or objects about a rig, and that the mechanism required in carrying out my invention may be comparatively 120 simple and inexpensive and may be designed and constructed so that it is convenient to apply to an ordinary draw works, and is convenient to operate. Further, the form, arrangement, and details of the mechanism may be 125 130

varied widely and still be within the broader aspects of my invention. In view of the nature of my invention I wish it considered broadly, and I do not limit myself to the particular details hereinabove set out but wish to reserve to myself any changes or variations that may appear to those skilled in the art and fall within the scope of the following claims.

10 Having described my invention, I claim:

1. In combination, a draw works including a frame and a horizontal drive shaft in the frame, a cam freely mounted on the shaft, an arm pivotally mounted on the frame to hang in cooperative engagement with the cam, means for connecting the arm and a part to be operated, and a clutch for connecting the shaft and cam.

2. In combination, a draw works including a frame and a horizontal drive shaft, a cam freely mounted on the shaft, an arm, means pivotally mounting the arm on the frame to hang in cooperative engagement with the cam, a clutch for connecting the shaft and cam, a yoke extending past the cam and connecting to the arm, and a flexible member for connecting the yoke with a part to be operated.

3. A well drilling apparatus including a draw works having a frame and a drive shaft, a cam freely mounted on the shaft, a clutch part attached to the cam, a complementary clutch part slidably keyed to the shaft, means for operating the last mentioned clutch part to move it into cooperative engagement with the first mentioned clutch part, an arm pivotally mounted on the frame to hang in cooperative engagement with the cam at the rear of the draw works, a spring operating to hold the arm in cooperative engagement with the cam, a yoke arranged to extend rearwardly past the cam, means for adjustably connecting the rear portion of the yoke with the arm, means for supporting the forward portion of the yoke, a flexible member connected with the forward portion of the yoke and adapted to be connected with a part to be operated, and rollers located at the front of the draw works to guide said flexible member.

4. A tong operating device for use in connection with a draw works having a shaft and a frame which includes a cam free on the shaft, an arm pivoted on the frame above the cam to normally hang in engagement with the cam, a yoke, means for connecting the yoke to the arm at any one of a plurality of points spaced longitudinally of the arm, means for connecting the yoke with the tongs, and a clutch on the shaft for connecting the cam with the shaft.

5. A tong operating device for use in connection with a draw works having a shaft and a frame which includes a cam free on the shaft, an arm pivoted on the frame above

the cam to normally hang in engagement with the cam, a yoke, means for connecting the yoke to the arm at any one of a plurality of points spaced longitudinally of the arm, means for connecting the yoke with the tongs, and a clutch on the shaft for connecting the cam with the shaft including a female member mounted on the cam, and a male member slidable on the shaft for cooperating with the female member.

6. An attachment for a draw works having a shaft and a frame which includes a sectional cam, means for securing the cam sections together on the shaft, an arm adapted to be pivotally mounted on the frame to hang in engagement with the cam to be operated by the cam, and means for controlling the co-operation between the arm and the cam including a clutch member mounted on the cam, and a clutch member on the shaft, the said clutch members being relatively axially shiftable into and out of cooperative engagement.

7. A device for use on the draw works of a well drilling apparatus for operating tongs which includes, a cam to be freely mounted on a shaft of the draw works, an arm to be pivotally mounted on the frame of the draw works in position to be engaged by the cam, spring means for holding the arm in engagement with the cam, means for connecting the arm with tongs, and a clutch to be mounted on the shaft including a member to be mounted on the cam, and a member rotatable with the shaft operable into driving engagement with the first-mentioned member.

8. An attachment for a draw works having a drive shaft which includes, a cam comprising sections to be assembled around the shaft, means for securing the sections of the cam together, a clutch including sections to be assembled around the shaft to form a releasable driving connection between the shaft and cam, means for securing the clutch sections together on the shaft, a pivotally mounted member operable by the cam, and means for connecting said member and a part to be operated.

9. An attachment for the draw works of a well drilling apparatus having a rotating shaft which includes a pivoted arm, a cam to be freely mounted on the shaft in position to engage the arm, means for connecting the arm with a part to be operated, a clutch for rotatably connecting the cam with the shaft including a part attached to the cam, a part on the shaft to rotate therewith and slide thereon, and means for sliding the last-mentioned part into engagement with the first-mentioned part to connect the two parts for rotation.

In witness that I claim the foregoing I have hereunto subscribed my name this 3rd day of July, 1923.
